ELECTRICAL RECEPTACLE FACE PLATE

Lee T. Bordner, Los Angeles, Calif., assignor to Sierra Electric Corporation, Gardena, Calif., a corporation of California

Filed June 1, 1965, Ser. No. 85,538

Term of patent 14 years

(Cl. D26—1)

FIG. 1.

FIG. 2.

FIG. 3.

FIG. 4.

FIG. 5.

FIG. 6.

FIG. 1 is a plan view of an electrical receptacle face plate embodying my new design;

FIG. 2 is a side elevational view thereof;

FIG. 3 is a left-end elevational view thereof;

FIG. 4 is a right-end elevational view thereof;

FIG. 5 is a cross-sectional view thereof taken on line 5—5 of FIG. 1; and

FIG. 6 is a cross-sectional view thereof taken on line 6—6 of FIG. 1, a portion of the bottom area being omitted for convenience of illustration.

The essential features of my design are shown in full lines.

I claim:

The ornamental design for an electrical receptacle face plate, substantially as shown and described.
